SKYLIGHT

Charles Raschka, Wauwatosa, Wis., assignor to
Super-Steel Products Company, Milwaukee,
Wis.

Application December 7, 1931. Serial No. 579,366

12 Claims. (Cl. 108—16)

The invention relates to improvements in skylights and particularly to hip or ridge skylight structures embodying improved features of construction.

5 An object of the invention is to provide a hip skylight structure with improved means for securing the hip bars to the curb bars.

Another object is to provide a ridge, hip, and rafter bar of a skylight with improved means to 10 facilitate securing of the respective caps thereover.

Another object is to provide a skylight structure with an improved cross bar to facilitate mounting and insure retention of glass sections 15 therein.

Another object is to provide a skylight structure incorporating improved features of construction which facilitates assembly and reduces labor and manufacturing costs.

20 The foregoing and such other objects of the invention as will appear hereinafter as the description proceeds, will be more readily understood from a perusal of the following specification, reference being had to the accompanying drawing, in which:

Fig. 1 is a fragmentary perspective view of a hip skylight.

Fig. 2 is a fragmentary sectional view taken substantially on line 2—2 of Fig. 1.

30 Fig. 3 is a sectional view of a rafter bar, taken on line 3—3 of Fig. 1.

Fig. 4 is a fragmentary plan, with parts broken away, of the improved union connecting the hip and rafter bars to the ridge bar and curb bar.

35 Fig. 5 is a fragmentary sectional view taken on line 5—5 of Fig. 4.

In hip skylight structures of usual construction, considerable difficulty and expense is encountered in fitting and securing the hip bars in 40 place, due, primarily, to the necessity of mitering the ends of said bars to insure tight joints.

The improved structure, as illustrated, generally, in Fig. 1, includes a substantially rectangular base or supporting frame 11 consisting of side curb bars 12 and end curb bars 13 joined at 45 the corners 14 in any known manner. A hip bar 15 extends upwardly and inwardly from each corner 14 of the frame and the converging bars at each end of the frame are joined at their other ends and secured to a ridge bar 16 in an improved manner to be later described. Usually each end of the hip bars 15 is mitered or otherwise cut to provide a tight weather-proof joint at its connection with the ridge bar and 50 with the frame 11. However, in the improved

structure suitable means is provided to simplify its mounting and reduce the manufacturing and assembly cost.

As shown in Figs. 1 and 4, a fitting or union 17 preferably comprising, substantially, a triangularly shaped box-like structure having its open side disposed upwardly, is provided at each corner of the frame 11 and is secured to said frame preferably by bolts 18 passing through the respective side walls 19 of said union. The two inclined side walls 19 of each union form a right angle which fits tightly into the inside corner of the frame. A vertically inclined wall 21 extends diagonally between the walls 19 and preferably is connected thereto by intermediate wall portions 22. This vertically inclined wall is pitched to receive squarely the lower square cut end of the hip bar 15 which is secured thereto in a suitable manner such as by bolts 23 passing through the wall 21. As shown, the fitting or union 17 is of sufficient size to admit a wrench or other tool while assembling.

Another box-like fitting or union 24 (Fig. 4) is secured to each end of the ridge bar 16 by bolts 25 which pass through the vertical wall 26 of said union and through angle clips 27 provided on each end of the ridge bar. End walls 28 extend at right angles to the wall 26 and are connected with a downwardly inclined wall 29 by diagonal vertically inclined walls 31. The 85 diagonal vertically inclined walls 31 each are adapted to meet squarely one of the square cut upper ends of hip bars 15 diverging upwardly and inwardly from the adjacent corners of the same end of the frame 11. The square cut upper ends of the hip bars 15 are secured to the respective walls 31 by bolts 32. The walls 28 and wall 29 are each adapted to receive the square cut upper end of the respective rafter bars 33 and 34 which are secured thereto by bolts 35 and 36, respectively. It will be noted that the union is arranged with its open end disposed upwardly to facilitate access thereto with a tool to hold bolts 25, 32, 35, and 36.

The ridge bar 16 has oppositely disposed 100 downwardly directed longitudinal flanges 37 and shoulders 38 to receive thereon the upper marginal edges of the upper sections of glass 39. The lower marginal edges of the glass sections 39 are adapted to be inserted into a recess 42 formed by providing spaced parallel flanges 43 and 44 on the upwardly disposed side of a cross-bar 45, rigidly secured to the rafters intermediate frame 11 and ridge bar 16.

The upper or retaining flange 43 of the cross- 110

bar 45 is, as shown in Fig. 2, substantially narrower than flange 44, and when a section of the glass 39 is to be mounted, said glass is positioned with its upper edge against the shoulder 38 whereby its lower edge clears the edge of flange 43, as shown in dotted lines, and rests upon flange 44. The glass section is then slid downwardly into the recess 42 and a felt or putty lining 46, having previously been inserted 10 therein, insures a weather tight joint. The space between the upper edges of the glass sections and the shoulders 38 are filled with felt or putty 47 and a suitable cap 48 having retaining flanges 49 is placed over the ridge bar to retain 15 the glass in place.

Ordinarily the cap 48 is secured in place by bolts passing through holes therein and engaging in tapped openings in the ridge bar. However, this structure is objectionable since it 20 often requires drilling and tapping of the holes while the parts are being assembled. As shown, this objection is overcome by providing, in the upper face of the protruding longitudinal rib 50 on the ridge bar 16, a longitudinal central 25 substantially T-shaped slot 51. Bolts 52 having their heads 53 retained in the slot 51 are arranged to pass upwardly through holes 54, previously provided in the cap 48, and nuts 55 are threaded on the extended ends of said bolts to 30 draw the cap tightly down against the upper marginal edges of the glass sections. The cross bar and ridge bar structure herein shown are applicable to any type of hip or ridge skylight other than the exemplary structure illustrated. 35 The rafter bars 33, 34, and 56, and also the hip bars 15 preferably are substantially like the ridge bar in cross section. As shown in Fig. 3, it will be noted however, that the marginal flanges 37' of the rafter bar 56 are not inclined, since the glass sections lie in a parallel 40 plane.

It will readily be apparent that the lower marginal edges of the glass sections 39 are positively held by the retaining edge or flange 43 on 45 the cross bar 45. In common practice such retaining means is not provided, which often results in the displacement of the glass sections or the development of leaks at the joints. The 50 putty or felt provided in the space between the remaining edges of the glass and shoulders 38 and 38' is fully protected from the weather by caps 48 and 48' and their retaining flanges 49 and 49'.

The union 24 joining the ridge, hip, and certain of the rafter bars also is covered by a cap 55 57 closed on its end to exclude water or other deteriorating agents. The union 17 also may be covered, to prevent accumulation of foreign matter therein.

Although an exemplary form of the improved skylight structure is shown in the accompanying drawing, and described in detail in the foregoing, it is to be understood that said structure 60 may embody various modifications in detail without departing from the spirit of the invention or the scope of the appended claims.

I claim:

1. A skylight structure comprising, in combination, a plurality of sections of glass, a ridge bar, said ridge bar having a central longitudinal rib providing a longitudinal shoulder on each side to support one marginal edge of certain of said glass sections, a cap adapted to overlie 70 said marginal edges of the glass sections, and a

central longitudinal T-shaped slot in said rib adapted to receive and retain the heads of a plurality of bolts extending upwardly through holes in said cap, and means threaded on the extended ends of said bolts to retain said cap 80 in place.

2. In a skylight structure, the combination of, a ridge bar, said ridge bar having a central rib formed with a longitudinal slot substantially T-shaped in cross section, a cap adapted to overlie said ridge bar, bolts having their heads anchored in said slot extending through openings in said cap, and means threadingly engaging the extended ends of said bolts to retain the cap 85 in place.

3. In a skylight structure, the combination of, a ridge bar, a longitudinal shoulder on each side of said ridge bar to support one marginal edge of each of a plurality of glass sections, said shoulders providing a longitudinal upwardly protruding rib, a cap adapted to be placed over said ridge bar, a central longitudinal slot in said rib adapted to receive and retain a plurality of bolts, said bolts extending through openings in said cap, and nuts threadingly engaging the extended ends of said bolts to draw the cap 90 tightly against the said marginal edges of the glass sections.

4. In a skylight structure, a frame consisting of substantially parallel side and end bars, a ridge bar, a fitting on each end of said ridge bar, a hip bar extending upwardly and inwardly from each corner of said frame toward the ridge bar, said hip bars connecting at their upper ends with the associated fitting on said ridge bar, and a connecting union of one piece in each corner of said frame to facilitate connection of the hip bars with said frame.

5. A skylight structure having, in combination, a substantially rectangular base frame including side and end members, a ridge bar, hip bars extending from the ends of said ridge bar one to each corner of said rectangular frame, and one piece unions one in each corner of said frame and one on each end of said ridge bar to facilitate connection of the hip bars thereto.

6. A skylight structure including a plurality of glass sections comprising, in combination, a substantially rectangular frame including side and end members, a ridge bar, hip bars two extending from each end of said ridge bar and diverging toward the respective corners of said frame, a fitting interposed between the end of each hip bar and the respective ends of the ridge bar, and the other ends of said hip bars being secured to a fitting connecting the respective corners of said frame, and said ridge bar having a T-shaped longitudinal slot on its top surface to receive means for retaining certain of said glass sections on said structure.

7. A ridge bar for a skylight structure having, in combination, a longitudinal flange on each side of a central rib in said ridge bar, a shoulder on each of said flanges to receive and support one marginal edge of a plurality of glass sections, and a longitudinal T-shaped slot in said central rib adapted to receive and retain a plurality of bolts therein for securing means on the ridge bar to retain said glass sections in 140 place.

8. A union for a skylight structure, including a rectangular frame and a hip bar, comprising, in combination, one side and one end wall arranged at right angles to each other to fit an 145

inside corner of said frame, and a vertically inclined wall extending diagonally between said side and end walls to receive one end of said hip bar in abutment therewith.

5 9. A union for a skylight structure, including a ridge bar and a plurality of hip bars, comprising, in combination, a vertically disposed wall adapted to be secured to one end of said ridge bar, and diagonally arranged vertically inclined walls extending outwardly from said vertical wall each adapted to receive one end of one of said hip bars in abutment therewith.

10 10. A union for a skylight structure, including a ridge bar and a plurality of hip bars, comprising, in combination, a vertically disposed wall adapted to be secured to one end of said ridge bar, and diagonally arranged vertically inclined walls extending on one side and inwardly from the ends of said vertical wall each adapted to receive one end of said hip bars in abutment therewith.

15 11. A union for a skylight structure, including

a ridge bar and a plurality of rafter and hip bars, comprising, in combination, a vertically disposed wall adapted to be secured to one end of the ridge bar, vertically inclined walls extending on one side from each end of said vertical wall, each adapted to receive in abutment therewith a rafter, vertically inclined converging walls extending from each side wall each adapted to receive in abutment one of said hip bars, and a connecting wall between said converging walls to receive a rafter in abutment therewith.

20 12. A union for a skylight structure including a ridge bar and a plurality of hip bars comprising, in combination, a vertically disposed wall adapted to be secured to one end of said ridge bar, and diagonally arranged vertically inclined walls extending outwardly from said vertical wall each adapted to receive one end of one of said hip bars in abutment therewith, said hip bars having square cut ends.
